UNITED STATES PATENT OFFICE.

THOMAS C. McDANIEL AND RICHARD M. FRAWLEY, OF ROCHESTER, NEW YORK.

WINDOW-SCREEN.

1,217,793.

Specification of Letters Patent. Patented Feb. 27, 1917.

Application filed April 26, 1916. Serial No. 93,786.

To all whom it may concern:

Be it known that we, THOMAS C. McDANIEL and RICHARD M. FRAWLEY, citizens of the United States, and residents of Rochester, in the county of Monroe and State of New York, have invented certain new and useful Improvements in Window-Screens, of which the following is a specification.

This invention relates to improvements in spring-controlled window screens. It has for its object a construction in which the screen is prevented from escaping from its vertical guideways, while being raised or lowered, and which at the same time permits 10 the screen to be removed after having been rolled up without disturbing the vertical guideways.

In the drawings:—

Figure 1 is a front view of a screen and 20 its housing;

Fig. 2 is a vertical section on the line *a—a* of Fig 1;

Fig. 3 is a partial sectional view, enlarged, 25 taken on the line *b—b* of Fig. 2; and

Fig. 4 is an enlarged vertical section, on the line *c—c* of Fig. 3.

The spring-actuated roller 1 of usual construction is supported on its shaft 2 by the end plates 3 of the housing 4. The screen 30 5 has at its lower edge the reinforcing strip 6, which moves in vertical guideways 7, 7 on the casing. The upper ends of the guideways 7, 7 terminate some distance below the roller, so that by permitting the screen to 35 roll up fully on the roller the ends of the reinforcing strip 6 are withdrawn from the guideways 7, 7, and the rolled up screen may be removed from the window.

But unless the housing 4 is removed for 40 the purpose of removing the screen, the housing bears yieldingly at its lower edge against the screen, on both sides of the frame, above the points where the guideways terminate, thus holding the reinforcing strip 45 6 in against the frame, so that it enters the guideways when drawn down from the uppermost position which it takes when the screen is wound up as far as it will go.

In order to keep the reinforcing strip 6 50 in its guideways 7, 7, while the screen is being raised and lowered, a cross-bar 8 is employed on the lower end of the screen, back of the reinforcing strip, that is slightly narrower than the distance between the sides of 55 the casing, so that as the screen is raised and lowered this cross-bar 8 is in close proximity

to the sides of the window frame and prevents one end of the reinforcing strip 6 from moving upwardly in advance of the other, as frequently occurs in manipulating 60 screens and curtains arranged in this manner.

A bolt 9 for locking the screen in extended position is shown. This is adapted to enter a hole in the side of the casing near 65 the sill.

The cross-bar 8 serves another function. It underlies a top rail 10 of the window frame so that when the screen is rolled up beneath the housing 4, this cross-bar 8 will 70 come in contact with the casing and prevent the screen from being wound up on the roller so as to carry it out of reach. As it is, the cross-bar 8 is accessible and affords an adequate grip when the screen is to be drawn 75 down.

The screen may be reinforced at intervals by spring strips 11 which are secured transversely of the screen. These strips prevent the sagging of the screen and at the same 80 time have their ends working in the guides.

What we claim as our invention and desire to secure by Letters Patent is:

1. In combination with a window frame, a roller mounted at the top of the frame, a closure adapted to be wound on the roller and overlapping the side members of the frame, guides on the front faces of said side members for the side edges of the closure, said guides being spaced at their upper ends 85 from the roller and the upper rail of the frame, a housing for the roller and the closure projecting below the upper rail of the frame, said housing being open at the rear and having a lower yieldingly mounted free edge arranged to permit the free edge of the closure to pass the same in either direction and lying in close proximity to the guide rails so that it acts as a guide to direct the free edge of the closure to the guides 90 when the free edge is withdrawn from the closure.

2. In combination with a window frame, a roller mounted at the top of the frame, a closure adapted to be wound on the roller and overlapping the front faces of the uprights of the frame at its side edges, guides for the side edges of the closure secured to the front faces of the uprights, said guides being spaced at their upper ends from the top rail of the window frame, a housing for the roller and the closure, the housing being 105 110 115

open at the rear below said top rail and having its free lower edge lying in close proximity to the guide rails so that it acts as a guide to direct the free edge of the closure to the 5 guide, and a cross bar secured to the free edge of the closure and lying between the uprights with its ends arranged to coöperate with the uprights to guide the closure to the guides and its upper part arranged to co- 10 operate with the under side of the top rail of the window frame to maintain the free edge of the closure in a position where it may be reached from the open rear side of the housing.

15 3. In combination with a window frame, a roller mounted at the top of the frame

above the lower surface of the top rail of the latter, a closure wound on the roller, said closure overlapping the side members of the frame and having means near its free edge 20 for coöperating with the under face of the top rail to limit the upward movement of the free edge of the closure, and a housing covering said roller, open at its rear below the top rail of the frame, and having a 25 yieldingly mounted free edge below said top rail, overlapping the side members of the window frame to bear upon the closure as the latter is drawn downwardly.

THOMAS C. McDANIEL.
RICHARD M. FRAWLEY.
